(57) **CLAIM**

The ornamental design for a water sanitizer system enclosure, as shown and described.

DESCRIPTION

FIG. 1 is a top perspective view of a water sanitizer system enclosure showing our new design.

FIG. 2 is a left side view thereof.

FIG. 3 is a right side view thereof.

FIG. 4 is a back view thereof.

FIG. 5 is a front view thereof.

FIG. 6 is a top view thereof; and,

FIG. 7 is a bottom view thereof.

The broken lines in the drawings depict portions of the water sanitizer system enclosure that form no part of the design.
